UNITED STATES PATENT OFFICE.

JACQUES LENTÉ, OF PARIS, FRANCE, ASSIGNOR TO SOCIÉTÉ ANONYME D'ESCAUT & MEUSE, OF PARIS (SEINE), FRANCE, A COMPANY OF FRANCE.

MANUFACTURE OF RETURN CONNECTIONS.

Application filed September 27, 1921. Serial No. 508,674.

To all whom it may concern:

Be it known that I, JACQUES LENTÉ, engineer, citizen of the French Republic, residing at Paris, France, have invented certain new and useful Improvements in the Manufacture of Return Connections, of which the following is a specification.

The present invention relates to a process for the manufacture of connections and in particular of those which are intended to form elements of tubular superheaters.

These connections, which are of U shape, are generally obtained, either in cast iron or cast steel. The elements are also sometimes united by direct forging of their end and brazing with the blowpipe.

These different means are far from giving entire satisfaction, and the object of the present invention consists in constructing connections of steel of the desired type by the aid of a process which is very simple, their relatively small thickness not being a cause of obstruction in the smoke tubes as is the case with the connections of cast iron or cast steel.

The accompanying figures, from 1 to 6, will permit of the easy comprehension of the different operations required for the process.

Figure 1 is a longitudinal sectional view of one form of tube from which the return connection is made.

Fig. 2 is a similar view of the preferred form of tube from which the return connection is made.

Figs. 3 and 4 are end views respectively of the tubes shown in Figures 1 and 2.

Fig. 5 is a sectional view of the tube shown in Figs. 2 and 4 after said tube has been bent into U-shape.

Fig. 6 is a vertical sectional view of the means for shaping the U-shaped tube.

The first operation consists in preparing the tubes of suitable length and shape by giving them by known means, a uniform extra thickening distributed over their periphery as is shown in Figures 1 and 3, or

preferably a local extra thickening, as is shown in Figures 2 and 4.

The tube in Figure 2 for example is afterwards bent into a U as shown in Figure 5, in which the piece is shown in section. The bending of the tube into the shape of the U is carried out in the second operation on the smallest possible radii which forging permits of. The extreme part corresponds to the reinforced portion of the tube in order to reduce the thinning caused by the bending of the tube into the U and also in order to retain an appreciable thickening.

The third operation, which shapes the connection, is carried out in a matrix of special form shown in Figure 6. The matrix is shown at 1 and the shaping punch at 2. Two mandrels 3, 3 ensure the calibration of the branches during the shaping operation. In Figure 6, the elbow before it is shaped is indicated by dotted lines and the finished connection by full lines.

Claims.

1. A process for the manufacture of a return connection, particularly intended to form an element of a tubular superheater, consisting in providing a tube with a thickened portion intermediate its ends, curving said tube into the form of an elbow, placing said elbow in a press and exerting pressure on the elbow to shape the metal of the elbow, and inserting mandrels in the ends of said elbow before exerting pressure on the same.

2. A process for the manufacture of a return connection, particularly intended to form the element of a tubular water heater, consisting in providing a tube with a locally thickened portion intermediate its ends, curving said tube into the form of an elbow, inserting mandrels into the ends of said elbow, and placing said elbow in a matrix and shaping the metal by a punch.

In testimony whereof I affix my signature.

JACQUES LENTÉ.
